(57) **CLAIM**

The ornamental design for a portion of a joystick handle, as shown and described.

DESCRIPTION

FIG. 1 is a perspective view of a portion of a joystick handle showing our new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof; and,
FIG. 7 is a bottom plan view thereof.

The broken line showing of the remainder of the handle in FIGS. 1-7, the bottom circular element in FIG. 7 and the joystick base in FIG. 1 is for illustrative purposes only and forms no part of the claimed design.
